UNITED STATES PATENT OFFICE.

JEFFERSON F. BROWN, OF MEMPHIS, TENNESSEE, ASSIGNOR TO U. S. BEDDING COMPANY, OF MEMPHIS, TENNESSEE, A CORPORATION OF GEORGIA.

SPRING BOTTOM.

Application filed June 15, 1925. Serial No. 37,379.

My invention relates to improvements in spring cushions, or bottoms, for use in bed springs, box springs, upholstered seats, automobile seats, and in other places where a 5 spring bottom or cushion is required.

An important object of the invention is to provide a guiding and supporting element, of simplified construction, which will cause the edge or border of the spring bottom, to 10 move substantially vertically, when depressed thus preventing perceptible lateral movement of the border which would result in the swaying of the coil springs, or outward bulging of the border.

15 Other objects and advantages of the invention will be apparent during the course of the following description.

In the accompanying drawings forming a part of this specification, and in which like 20 numerals are employed to designate like parts throughout the same,

Figure 1 is a fragmentary plan view of a spring bottom embodying my invention,

25 Figure 2 is a transverse section taken on line 2—2 of Figure 1,

Figure 3 is a perspective view, parts broken away, of the supporting and guiding arm, and,

30 Figure 4 is a perspective view of a modified form of the invention, parts broken away.

In the drawings, wherein for the purpose of illustration is shown a preferred embodiment of my invention, the numeral 5 designates the lower frame of the spring bottom, 35 preferably formed of angle irons, as is well known. This lower frame has the usual coil springs 6, mounted upon and attached to the same, by the usual means employed in the art. The upper frame of the spring bottom is 40 designated by the numeral 7, and this frame may be formed of a wire or rod, possessing suitable stiffness. This frame constitutes a border, and the upper ends of 45 the springs 6 are suitably secured to each other, and to this border frame, as is well known in the art.

The invention resides principally in the provision of means to cause the border frame 50 7 to move vertically, without partaking of substantial lateral movement. I have shown two of these devices, designated as a whole by the numeral 8, but it is of course understood that any suitable number of these devices may be employed, in connection with

the border frame, as may be found advantageous.

Each control device embodies a rigid arm 9, preferably formed of strap iron, which is preferably twisted at 10, so that it may be 60 bent at its end into an eye 11, to surround the rod or wire of the border frame 7. The border frame 7 is preferably circular in cross section, and hence the eye 11 is pivoted thereon. The arm 9 is angularly arranged 65 and inclines downwardly toward its inner end, and is then bent into a horizontal portion 11^a. This horizontal portion has its inner end pivotally connected, as shown at 12, with an upstanding link 13, which is 70 pivoted at 14, to a stationary transverse rail 15. This transverse rail is rigidly attached to the lower frame 5. The link 13 is adapted to swing in a vertical plane, transversely of the spring bottom, as shown. Disposed 75 outwardly of and adjacent to the vertical link 13 is a vertical stationary guide plate 16, riveted or otherwise rigidly attached to the rail 15, as shown at 17. This guide plate is provided with an inclined slot 18, extending downwardly in an inward direction, and this slot receives a guide pin 19, rigidly attached to the horizontal end portion 11^a of the arm 9.

When the upper border frame 7 is depressed, adjacent to its border, such border moves downwardly, but it is positively held against outward lateral movement, and is caused to travel in a substantially vertical plane, by virtue of the inward movement of 85 the guide arm 9, which as it is lowered, also partakes of an inward longitudinal movement, by virtue of the inclination of the slot 18.

In Figure 4 I have shown a modified form 95 of the device. In this form, each control device embodies a straight inclined rigid arm 20, preferably formed of strap iron, which is preferably twisted at 21, so that it may be bent at its upper end into an eye 22, to surround and pivotally receive the border frame 7. The lower end of the arm 20 carries a headed stud 23, slidable within an elongated horizontal slot 24, formed in a stationary plate, in the form of a rail 25, 100 corresponding to the rail 15, and attached to the lower frame 5, as shown. The lever 20 is pivoted between its ends, as shown at 26, with a vertically swinging link 27, which is pivoted to the plate or rail 25, as shown 105 110

at 28. The control device is of course used with the same spring bottom, as illustrated in Figures 1 and 2, wherein the border frame is supported from the lower frame by means 5 of the coil springs 6.

It is thus seen that as the border frame 7 is depressed, it can not move laterally and outwardly, as the arm 20 will be shifted inwardly or generally horizontally.

- 10 The device is particularly useful when springs are compressed and packed for shipment, as the border is kept straight and cannot become bent or forced out of its proper shape. A mattress spring or box spring, 15 equipped with the device, is very advantageous as the edge or border of the same cannot sag or move outwardly, when depressed, so that it would contact with a wooden bed, or the like, scratching or injuring the same.
- 20 It is to be understood that the forms of my invention herewith shown and described are to be taken as preferred examples of the same, and that various changes in the shape, size, and arrangement of parts may be re- 25 sorted to without departing from the spirit of my invention or the scope of the subjoined claims.

Having thus described my invention, I claim:

- 30 1. The combination with a spring bottom comprising a lower frame and an upper border frame and springs connected therewith, of a guide arm pivotally connected

with the border frame and inclined downwardly therefrom and projecting inwardly 35 with relation to the border frame, said guide arm being provided at its inner end with a substantially horizontal portion, a vertically swinging link pivotally connected with the substantially horizontal portion, a stationary 40 guide plate arranged adjacent to the substantially horizontal portion and having an inclined slot projecting downwardly in an inwardly direction, and an element carried by said substantially horizontal portion and 45 slidable within the inclined slot.

2. The combination with a spring bottom comprising a lower frame and an upper border frame and springs connected therewith, of a guide arm pivotally connected 50 with the border frame and inclined downwardly therefrom and projecting inwardly with relation to the border frame, an up- 55 standing stationary guide plate arranged adjacent to the inner portion of the guide arm and attached to the lower frame and having an inclined slot projecting downwardly in an inwardly direction, a pin carried by the inner portion of the guide arm and slidable within the inclined slot, and an upstanding 60 link arranged upon the inner side of the stationary guide plate and pivotally connected with the inner end of the guide arm and pivotally connected with the lower frame.

In testimony whereof I affix my signature.
JEFFERSON F. BROWN.
